UNITED STATES PATENT OFFICE.

LAURENCE E. TOPHAM, OF WENHAM, MASSACHUSETTS, ASSIGNOR TO UNITED SHOE MACHINERY CORPORATION, OF PATERSON, NEW JERSEY, A CORPORATION OF NEW JERSEY.

MANUFACTURE OF IRREGULAR OBJECTS.

Application filed June 14, 1928. Serial No. 285,468.

This invention relates to the manufacture of irregular objects in a copying lathe and is illustrated as embodied in a lathe for turning lasts.

5 It is often desirable in last or model making to alter a given model by twisting portions of it relatively to others around its longitudinal axis. This problem has a peculiar application to the fitting of new style fore-
10 parts to standard heel parts, where it is sometimes necessary to distort the rear end of the forepart a little in order to make it fit properly the front end of the standard heel part.
15 In its method aspect, the present invention solves this problem by relatively twisting the thin laminæ, into which the model may be regarded as divided, around the longitudinal axis of the model, to which the laminæ
20 are perpendicular, in reproducing them in the block, and this method of reproduction, having several aspects which will be better understood after consideration of the annexed specification, forms an important part
25 of the invention.

In its machine aspect, the invention provides a mechanism whereby the method can be practiced, and lasts of the desired character produced. By means of this machine I
30 am enabled to produce an effective relative rotational displacement during the reproduction from the given model, of one of the four primary instrumentalities of the copying lathe (the model holder, block holder, model wheel and cutter), around the axis of rotation of the model or block, relatively to the others. Such displacement will persist through at least one rotation of the model and block in order that the one or more thin
35 slices or laminæ of the model reproduced in the work during such rotation may be rotated relatively to those adjacent to them.

40 In the illustrated machine this object is accomplished by displacing the model wheel angularly around the axis of rotation of the model. This machine comprises mechanism for moving the model wheel in a plane perpendicular to the axis of the model and for keeping it, in that plane, at a predetermined
45 uniform angular displacement from its standard position (that position which is characteristic of exact 1:1 reproduction), as seen from the axis of rotation of the model. This will cause the model section or lamina

perpendicular to the axis of rotation of the 55 model, which is being reproduced, to lie in a correspondingly rotated position in the block relatively to those formed with the model wheel in its standard position, and if the predetermined angle above mentioned is 60 changed during the cut from one end of the last to the other, as is provided for, the model will be reproduced in twisted form in the block.

This and other features of the invention in 65 its machine aspect will be better understood from a consideration of the illustrated machine as described in the annexed specification and shown in the drawings, in which—

Fig. 1 is a sectional elevation of a machine 70 embodying the invention in its machine aspect;

Fig. 2 is a plan of the model wheel carriage of the machine;

Fig. 3 is a diagram; and

Fig. 4 is a plan of the entire machine.

A mechanical description of the machine will be first given, followed by its theory and a discussion of its operation.

The swing frame of the illustrated last 80 lathe comprises arms 10, 10 extending from a heavy pivot shaft 12, as shown more in detail in my application Serial No. 530,214, filed January 18, 1922. Pivoted to a stud 14 on one of the arms 10 is a link 16 which 85 extends to the back of the machine and is pivoted at 18 to a fanboard 20. The fanboard 20 is pivoted at 22 to the frame of the machine. The illustrated fanboard has nothing to do with width grading, as will be 90 seen, but is similar in shape, appearance and movement to the ordinary width grading fanboard and has therefore herein been called by this name.

A model wheel carriage 24 is arranged 95 to slide longitudinally of the machine on guides in the ordinary manner and has an upwardly extending standard 26 in which is mounted a model wheel carrying slide 28 arranged to slide forward and backward in 100 the standard. This slide effects the horizontal component of the motion of the model wheel necessary to produce its angular displacement about the model axis, which has been mentioned above. The slide 28 is 105 moved as follows. It contains a hole 30 through which extends a spindle 32 mounted in the standard 26, the hole permitting free

backward and forward movement of the slide. A cam member 34 is mounted on the spindle 32 and is oscillated on the axis of this spindle by toothed gearing 36, one element of which is mounted upon the cam member 34 and the other upon a bell-crank 38 pivoted at 40 on the standard 26. The bell-crank 38 is operated by a link 42—44—46 connecting it to the fanboard 20 (the notation 42—44—46 and similar expressions indicating that the link 44 is pivoted to its connected members at 42 and 46). The connection at 46 is a sliding one, to a rod 47 integral with the fanboard (Fig. 2), to permit the model wheel carriage to slide along the fanboard. A model wheel 48 is carried by a spindle 52 mounted in the model wheel slide 28, the axis of which spindle is parallel to the direction of travel of the model wheel carriage. The spindle 52 is rotatably mounted in the end of a lever arm 54 which is pivoted at 56 upon the slide 28 with the pivotal axis 56 extending through the slide and playing forward and backward with the slide in a cut-out 57 in the standard 26. The further end of the axis 56, as seen in Fig. 1, carries a lever arm 58 extending in the opposite direction to the arm 54 and having on its end a cam roll 60 which runs in a cam slot 62 in the cam member 34. Thus the movement of the fanboard is communicated through the gearing 36 to the cam member 34 to the lever arm 58, spindle 52 and model wheel slide 28.

The vertical movement of the model wheel 48 is effected as follows. The lever arm 58 is connected by a link 64—66—68 to a bell-crank 70—72—74 (this nomenclature indicating that the bell-crank has arms 70—74 and is pivoted at 72) pivoted on the standard 26. The pivot 72 of this crank extends through the standard 26 and the arms are on opposite sides of the standard. The arm 74 of this bell-crank is adjustably connected by a link 76—78—80 to the fanboard 20. The connection at 80 is a roll which can be adjusted up and down on the fanboard and can slide longitudinally on it as the model wheel carriage moves. Thus the fanboard movement will move the lever arm 58 vertically, causing a corresponding movement of the model wheel 48.

The model wheel 48 is itself (Fig. 2) mounted on a little spindle 79 mounted integrally upon the spindle 52 but making a horizontal angle of about 30° therewith for the purpose explained in United States Letters Patent No. 1,330,841, granted February 17, 1920, on the application of F. S. Buck, and the center 81 of the wheel is in the central axis of the spindle 52. As stated, the spindle 52 with the spindle 79 and model wheel carried on it are rotatable in the end of the lever arm 54. They are rotated by the crank arm 82 mounted upon an enlargement

83 (Fig. 2) connecting the spindles 52 and 79, and the crank arm 82 is connected by a link 84—86—88 to the arm 90 of the bell-crank 90—96—92 which is rotatably mounted upon the axis 56. The members 82, 86, 90, 54 form a parallelogram. The arm 92 of the bell-crank last referred to is connected by a link 94—96—98 to the arm 100 of a bell-crank 100—102—104 pivoted on the standard 26 at 102 and the bell-crank arm 104 is connected by a link 106—108—110 to the link 78. Thus the movement of the fanboard is enabled to rock the shaft 52 with the model wheel axis 79 carried by it.

A link 107—109—111 connects the link 78 to a block 112 which is adjustable in a circular slot 114 formed in a correspondingly shaped member 115 pivoted at 116 on the model wheel carriage. The block 112 is also connected by a link 111—120—122 to the end of a crank 124 pivoted at 126 to the standard 26 and carrying a toothed segment 128 which cooperates with a worm 130 on a shaft 132 operated by a handle 134. This handle, therefore, will adjust the block 112 in the circular slot 114 and thus move the link 109 to adjust the roll 80 on the fanboard 20.

A cam 136 pivoted at 137 on the model wheel carriage cooperates with a cam roll 138 on the end of a crank arm 140 mounted integrally with the member 115. The crank arm is pulled upwardly to hold the cam roll in contact with the cam by a spring 141. The cam is rotated in exact timed relation to the model by a gear 142 integral with the cam and driven from a toothed shaft 144 which extends longitudinally through the machine, allowing the gear 142 to maintain contact with it in all positions of the model wheel carriage.

The model and block are driven as follows. Mounted on the shaft 144 at the end of the main frame is a gear 146 which, through a suitable gear train located in the main frame, rotates a model 148, carried by the swing frame, by means of a gear 150 pivoted upon the axis of the shaft 12 and engaging a gear 152 mounted on a spindle 154 in the swing frame, to which gear 152 is rigidly connected, another gear 156 engaging a gear 158 mounted on the model spindle 160. The gear 156 has just half as many teeth as the gear 158 which, as explained in my copending application Serial No. 530,214, hereinbefore referred to, will cause a radial plane of the model 148 which passes through the standard position of the model wheel center to continue to pass through that position irrespective of rotation of the swing frame itself.

The means for suspending the model 148 and the work block 162 in the swing frame, the cutter carriage 163 carrying the cutter in an angular relation to the axis of rotation of the block similar but opposite to

that described between the model wheel and the axis of rotation of the model, and the drive of the model wheel and cutter carriages in opposite directions by a right and left screw 165, are all substantially as explained in my application Serial No. 530-214 and need not be discussed in detail here.

The theory of the machine will next be explained. In order to design the machine a so-called "mean radius" of the model is empirically adopted on which to base the performance of the machine. This is indicated at 164 in Fig. 3, the swing frame 10 being swung out to the position it would take if the end of this radius of the model 148 lay on the face of the model wheel 48. An arc 166 is described from the center 160 as center with the distance 160-81 as radius, 81 in Fig. 3 being the normal position of the model wheel center, that is, the position taken by it when the cam roll 60 is on the center 32 (Fig. 1), and when the spindle 52 is in the same horizontal plane with the centers 56 and 32. (This is the position characteristic of exact 1:1 reproduction. It is in exact alinement with the cutter center.) The shape of the cam slot 62 is determined by carrying the center 81 (Fig. 3) around the arc 166, as at 81^a, keeping the fulcrum 56 of the lever 54-58, as at 56^a, in the line 81-32 (Fig. 3) along which it slides by the movement of the slide 28. The path of the cam roll 60 is then plotted as the curve 62 (Fig. 3), only the lower half of which is there shown. The curve 62 will not be circular, and the upper and lower branches of it will not necessarily be alike.

The desired angular position of the cam roll 60 along this curve, that is, the position which will effect, for example, a 5° displacement of the model wheel center 81 around the chosen position of the model center is obtained by a suitable setting of the handle 134, which adjusts the link 78 up and down the fanboard 20, the position of which is determined by the adopted position of the swing frame 10, and through the bell-crank 70-72-74 and the link 64-66-68, determines the position of the cam roll 60 in the cam slot 62. Any setting of the handle 134 will thus swing the model wheel center 81 through the corresponding angle on a circle about the adopted position of the model center, and will thus displace the center of the model wheel 48 angularly about the center 160 relatively to the cutter (or to the standard position of the model wheel).

If now the model in Fig. 3 be conceived to rotate so as to bring the end of a longer radius 164' on the face of the model wheel, moving the center 160 in Fig. 3 to 160', and the design of the cam slot 62 repeated for this condition of things, as shown by the primed numerals in Fig. 3, it will be found that the corresponding cam slot 62' (Fig. 3)

will intersect the cam slot 62 at the point 32 and also at the point corresponding to the intersection at 81^b of the two arcs 166 and 166'. In practice only a very small portion of the arcs 62, 62', near the point 32, will be used, and this portion of the arc 62', though very slightly different in shape from the corresponding portion of the arc 62, can be regarded merely as a slightly rotated position of the arc 62 itself, around the point 32. The error due to the adoption of the same shape of cam slot for all conditions is so small as to be regarded as immaterial. The proper angular position of the cam slot about the center 32 is, however, important and is secured by the mechanism 36-38-40-42-44-46. As the model turns, the swing frame swings and moves the fanboard 20 correspondingly, and the above-mentioned mechanism is so designed as to throw the cam slot 62 into the proper position for any position of the swing frame 10.

The mechanism connecting the handle 134 with the link 78 must be laid out by trial. Preferably all the mechanism will be laid out to fit exactly the conditions corresponding to the mean model radius and to the zero model radius, when it will be well enough adapted to other conditions.

In another way of looking at the matter, suppose the swing frame 10 (Figs. 1 and 3) to be swung outward. The fanboard 20, the lever 54-58, and the cam slot 62 will swing clockwise. The radius 164 (Fig. 3) will always continue to make the same angle with the line 160-81 because of the gear relation 156-158, and will swing counterclockwise as the point 160 moves along the circle 81-160 about the center 12, and the movement of the model wheel center 81 will just keep the point 160 on this radius.

The effect of this construction is easily seen. The model wheel will always contact with the model at a point on a model radius which makes a constant angle with the line 160-81. This line 160-81 represents also the line joining the axis of the block with the cutter center, so that the whole model section (perpendicular to the axis of rotation 160), which is then under treatment when reproduced in the block will be shifted around in space about this axis relatively to its position in the model, if the cam 136 is circular. If the cam 136 is not circular, or if the handle 134 be moved during one revolution of the model, the model section will be distorted in the block, and different parts of it when reproduced in the block, will be angularly shifted around the axis of rotation of the model and block by varying amounts.

In case the lathe has its model wheel and cutter mounted on axes parallel to the model and block axes, nothing further than the

mechanism already discussed is necessary for proper performance. In the disclosed lathe, however, the axes of the model wheel and cutter are similarly oblique to the axes of the model and block, respectively, and it is necessary to preserve the similarity of this relation in the revolution of the model wheel about the center of the model, that is, the model wheel axis 79 as well as the model 10 wheel center 81, must be revolved. This is accomplished by the parallelogram 54—82—86—90 and its attached crank 92, operated by the link 96, bell-crank 100—102—104 and links 108, 78, from the fanboard. This 15 mechanism is laid out by trial as suggested above. The rotation of the spindle 52 on its own axis necessary to turn the spindle 79 through the proper angle is obviously equal to the angular movement of the center 81 20 about the then position of the model center 160.

The preceding theoretical description has proceeded under the theory that the member 115 has remained motionless, as it would do 25 if the cam 136 were circular. If such a cam were used, and the handle 134 set and left undisturbed, the last cut would be exactly like the model, but the last and model would be relatively angularly displaced in the machine about their common axis 160. If the setting of the handle 134 be changed as the cutting proceeded, so as to change the amount of the revolution of the model wheel center about the model center at different 30 points along the length of the last, the last produced will have its different parts lying one after the other along its longitudinal axis, relatively twisted or rotated around this axis. This change in setting the handle 35 134 will ordinarily be slow so that the relative rotation between the laminae formed during two successive rotations of the block will be small. Such rotation is herein termed "differential".

45 This phenomenon can be regarded from two points of view. The model can be regarded as composed of a series of parallel laminae all perpendicular to its axis of rotation 160, and these laminae will be relatively angularly displaced about the axis 160. The model can also be regarded as being composed of a series of wedge-shaped 50 sectors all radiating from the axis 160, and the procedure just described will bend or warp these sectors.

The cam 136, if non-circular, as shown in Fig. 1, moves the member 115, and since the cam rotates synchronously with the model, it effects a cycle of movement of the model 60 wheel around the model axis 160 in each revolution of the model. Consider, as before, the model as divided into a large number of sectors by equally angularly spaced planes all passing through the axis 160. The 65 effect of the cam 136 is to reproduce these

planes in the block as planes, but in unequally angularly spaced relation to one another, causing some of the sectors to be thickened and others to be thinned. It produces the same effect as would a cycle of 70 varying settings of the handle 134, the length of the cycle corresponding with a rotation of the model.

By the combined use of the handle 134 and the cam 136, the effects of the cam cycle can 75 be magnified or diminished by changing the handle setting, at different points along the length of the last.

It might be stated that the movement of the model wheel around the model center 80 is zero when the cam roll 60 is over the center 32, and that this happens when the roll 80 is on the center 22. At such times the distance from the center 107 to the center 116 is equal to the length of the link 109, 85 so that by setting the pivot 111 to the center 116, by the handle 134, this neutral condition can be maintained.

Obviously, several points of view as to the effect produced by the mechanism are proper. For example, the model may be regarded as distorted and reproduced, as so distorted, in the block: or the distortion may be regarded as originating in the block itself during the reproduction from an un-distorted model.

Having thus described my invention, what I claim as new and desire to secure by Letters Patent of the United States is:

1. That improvement in methods of reproducing irregular objects which consists in reproducing in a block substantially parallel sections of a model differentially rotated upon one another around an axis perpendicular to their planes. 100

2. That improvement in methods of reproducing irregular objects which consists in differentially rotating substantially parallel plane sections of a model about an axis perpendicular to their planes, and reproducing them, so rotated, in a block. 110

3. That improvement in methods of reproducing irregular objects which consists in automatically reproducing in a block substantially parallel sections of a model differentially rotated upon one another around an axis perpendicular to their planes. 115

4. That improvement in methods of reproducing irregular objects which consists in automatically differentially rotating substantially parallel plane sections of a model about an axis perpendicular to their planes, and reproducing them, so rotated, in a block. 120

5. That improvement in methods of reproducing irregular objects which consists in reproducing in a block substantially parallel sections of a model differentially rotated upon one another around an axis perpendicular to their planes according to a predetermined law. 125

6. That improvement in methods of reproducing irregular objects which consists in differentially rotating according to a predetermined law substantially parallel plane sections of a model about an axis perpendicular to their planes, and reproducing them, so rotated, in a block. 5
7. That improvement in methods of reproducing irregular objects which consists in reproducing in a block those plane sections of a model which radiate from a given line, the sections being reproduced in the block in rotated positions about the reproduction of the line. 10
8. That improvement in methods of reproducing irregular objects which consists in reproducing in a block those plane sections of a model which radiate from a given line, the sections being reproduced in the block 20 in rotated positions about the reproduction of the line according to a predetermined law. 15
9. That improvement in methods of reproducing irregular objects which consists in reproducing in a block those plane sections of a model which radiate from a given line, the sections being reproduced in the block 30 in relatively rotated positions about the reproduction of the line. 25
10. That improvement in methods of reproducing irregular objects which consists in reproducing in a block those plane sections of a model which radiate from a given line, the sections being reproduced in the block 35 in relatively rotated positions about the reproduction of the line according to a predetermined law. 30
11. That improvement in methods of reproducing irregular objects which consists in rotating around a line in a model those plane sections of the model which pass through that line, and reproducing them, thus rotated, in a block. 40
12. That improvement in methods of reproducing irregular objects which consists in relatively rotating around a line in a model those plane sections of the model which pass through that line, and reproducing them, thus rotated, in a block. 45
13. That improvement in methods of reproducing irregular objects which consists in reproducing in warped positions in a block those plane sections of a model which radiate from a given line in the model. 50
14. That improvement in methods of reproducing irregular objects which consists in warping the plane sections of a model which radiate from a line in the model, and reproducing them, thus warped, in a block. 55
15. That improvement in methods of reproducing irregular objects which consists in relatively warping the plane sections of a model which radiate from a line in the model, and reproducing them, thus warped, 60 in a block. 65
16. That improvement in methods of reproducing irregular objects which consists in reproducing those plane sections of a model which radiate from a given line in the model, in warped and relatively rotated 70 positions about the reproduction of the line. 75
17. That improvement in methods of reproducing irregular objects which consists in warping the plane sections of a model which radiate from a line in the model, relatively rotating them about the line, and reproducing them, thus warped and rotated, in a block. 80
18. In a copying lathe, means for holding a model and a block, copying and cutting 85 instrumentalities for following similarly around the model and the block to reproduce the model in the block, and means for relatively revolving the said instrumentalities around the model and block, respectively. 85
19. In a copying lathe, means for holding a model and a block, copying and cutting instrumentalities for following similarly around the model and the block to reproduce the model in the block, and means for relatively revolving the said instrumentalities 90 around the model and block, respectively, and for holding them in their relatively revolved positions. 90
20. In a copying lathe, a model wheel, a tool, holders arranged to rotate a model and a block relatively against the model wheel and tool, respectively, normally at equal angular velocities, and means for varying the ratio of the said angular velocities. 100
21. In a copying lathe, a model wheel, a tool, holders arranged to rotate a model and a block relatively against the model wheel and tool, respectively, normally at equal angular velocities, and means for automatically 105 varying the ratio of the said angular velocities. 105
22. In a copying lathe, a model wheel, a tool, holders arranged to rotate a model and a block relatively against the model wheel 110 and tool, respectively, normally at equal angular velocities, and means for automatically varying the ratio of the said angular velocities in a cycle corresponding to each rotation of the model and block. 110
23. In a copying lathe, a model wheel, a tool, holders arranged to rotate a model and a block relatively against the model wheel and tool, respectively, normally at equal angular velocities, means for automatically 120 varying the ratio of the said angular velocities in a cycle corresponding to each rotation of the model and block, and means for varying the cycle in different portions of the model and block. 120
24. In a copying lathe, a model wheel, a tool, holders arranged to rotate a model and a block against the model wheel and tool, respectively, at normally equal angular velocities, and means for angularly relatively 125
- 130

displacing the model wheel and tool around the axes of rotation of the model and block respectively.

25. In a copying lathe, a model wheel, a tool, holders arranged to rotate a model and a block against the model wheel and tool, respectively, at normally equal angular velocities, and means for angularly relatively displacing the model wheel and tool around the axes of rotation of the model and block respectively and for maintaining the said relative displacement during a number of rotations of the model and the block.

26. In a copying lathe, a model wheel, a tool, holders arranged to rotate a model and a block against the model wheel and tool, respectively, at normally equal angular velocities, and means for angularly relatively displacing the model wheel and tool around the axes of rotation of the model and block, respectively, in a cycle corresponding to the rotation period of the model and block.

27. In a copying lathe, a model wheel, a tool, holders arranged to rotate a model and a block against the model wheel and tool, respectively, at normally equal angular velocities, means for angularly relatively displacing the model wheel and tool around the axes of rotation of the model and block, respectively, in a cycle corresponding to the rotation period of the model and block, and means for varying the cycle of relative displacement at will.

28. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively moving said four primary instrumentalities to reproduce in the block parallel sections of the model relatively rotated on one another around an axis perpendicular to their planes.

29. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively moving said four primary instrumentalities to rotate upon one another parallel sections of the model, about an axis perpendicular to their planes, and reproduce them, so relatively rotated, in the block.

30. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively moving said four primary instru-

mentalities to rotate relatively to one another about a line in the model, plane sections of the model passing through the line and reproducing them, so relatively rotated, in the block.

31. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively moving said four primary instrumentalities to reproduce plane sections of a model radiating from a line thereof, in the block in positions relatively rotated about the reproduction of the line.

32. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively moving said four primary instrumentalities to warp plane sections of a model passing through a given line thereof, and to reproduce them, so warped, in the block.

33. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively moving said four primary instrumentalities to reproduce in the block plane sections of the model radiating from a given line thereof, in warped positions.

34. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively shifting the model wheel and the tool about the axes of rotation of the model and block respectively.

35. In a copying lathe, four primary instrumentalities, viz, a model wheel, a tool, and holders arranged to rotate a model and a block against the model wheel and tool respectively, the contact between the model wheel and model controlling the depth of cut of the tool in the block, means for relatively angularly shifting the model wheel and the tool about the axes of rotation of the model and block respectively, and means for maintaining the angular shift during a number of rotations of the model and block.

36. In a copying lathe, four primary instrumentalities, viz, a model wheel, a tool, and holders arranged to rotate a model and a block against the model wheel and tool

- respectively, the contact between the model wheel and model controlling the depth of cut of the tool in the block, means for relatively angularly shifting the model wheel and the tool about the axes of rotation of the model and block respectively, and means for varying the amount of relative angular shift.
37. In a copying lathe, four primary instrumentalities, viz, a model wheel, a tool, and holders arranged to rotate a model and a block against the model wheel and tool respectively, the contact between the model wheel and model controlling the depth of cut of the tool in the block, means for relatively angularly shifting the model wheel and the tool about the axes of rotation of the model and block respectively, and means automatically for varying the amount of relative angular shift.
38. In a copying lathe, four primary instrumentalities, viz, a model wheel, a tool, and holders arranged to rotate a model and a block against the model wheel and tool respectively, the contact between the model wheel and model controlling the depth of cut of the tool in the block, means for relatively angularly shifting the model wheel and the tool about the axes of rotation of the model and block respectively, and a cam for varying the amount of relative angular shift.
39. In a copying lathe, four primary instrumentalities, viz, a model wheel, a tool, and holders arranged to rotate a model and a block against the model wheel and tool respectively, the contact between the model wheel and model controlling the depth of cut of the tool in the block, means for relatively angularly shifting the model wheel and the tool about the axes of rotation of the model and block respectively, and means automatically for varying the amount of relative angular shift during one revolution of the model and block.
40. In a copying lathe, four primary instrumentalities, viz, a model wheel, a tool, and holders arranged to rotate a model and a block against the model wheel and tool respectively, the contact between the model wheel and model controlling the depth of cut of the tool in the block, means for relatively angularly shifting the model wheel and the tool about the axes of rotation of the model and block respectively, and means automatically for varying the amount of relative angular shift during one revolution of the model and block.
41. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively angularly shifting the model wheel and the tool about the axes of rotation of the model and block respectively comprising a pivoted member carrying the model wheel.
42. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively angularly shifting the model wheel and the tool about the axes of rotation of the model and block respectively comprising a slide and a member pivoted on the slide and carrying the model wheel.
43. In a copying lathe, four primary instrumentalities, viz, a model wheel, a tool, and holders arranged to rotate a model and a block against the model wheel and tool respectively, the contact between the model wheel and model controlling the depth of cut of the tool in the block, and means for relatively angularly shifting the model wheel and the tool about the axes of rotation of the model and block respectively comprising a slide and a member pivoted on the slide and carrying the model wheel, and means for controlling the slide and the pivoted member.
44. In a copying lathe, three primary instrumentalities, viz, a model wheel, a tool, and a swing frame having holders arranged to rotate a model and a block against the model wheel and tool respectively, the contact between the model wheel and model controlling the depth of cut of the tool in the block, means for relatively angularly shifting the model wheel and the tool about the axes of rotation of the model and block respectively comprising a slide and a member pivoted on the slide and carrying the model wheel, and means, governed by the swing frame, for controlling the slide and the pivoted member.
45. In a copying machine, a tool, a swing frame arranged to carry a model and block, a lever arranged for a movement of combined rotation and translation and carrying a model wheel, a connection between the swing frame and the lever arranged to rotate the lever as the swing frame moves, and a cam connected to the swing frame to cause the translatory movement of the lever, the said cam and connections being arranged to keep the model wheel center in a plane passing through the axis of the model and making a predetermined fixed angle other than zero with a plane passing through the tool center and the axis of rotation of the block.
46. In a copying lathe, a lever carrying a model wheel on one end, a slide carrying the pivot of the lever, a pivoted cam engag-

ing the other end of the lever, a swing frame and a connection between the swing frame and the cam arranged to move the cam, and a connection between the swing frame and the lever to move the second-named end of the lever on the cam.

47. In a copying lathe, a lever carrying a model wheel on one end, a slide carrying the pivot of the lever, a pivoted cam engaging the other end of the lever, a swing frame and a connection between the swing frame and the cam arranged to move the cam, and a connection between the swing frame and the lever to move the second-named end of the lever on the cam, the first said connection being invariable and the second said connection being adjustable.

48. In a copying lathe, a swing frame, a model wheel carriage, a slide mounted therein, a lever pivoted on the slide and carrying a model wheel on one of its ends, a cam pivoted on the model wheel carriage and controlling the other end of the lever, a connection between the swing frame and the cam to rock the cam, a fanboard linked to the swing frame, mechanism connecting the lever and the fanboard to move the second-named end of the lever on the cam, and means for adjusting the connection between the mechanism and the fanboard.

49. In a copying lathe, a swing frame, a model wheel carriage, a slide mounted therein, a lever pivoted on the slide and carrying a model wheel on one of its ends, a cam pivoted on the model wheel carriage and controlling the other end of the lever, a connection between the swing frame and the cam to rock the cam, a fanboard linked to the swing frame, mechanism connecting the lever and the fanboard to move the second-named end of the lever on the cam, and means comprising a second cam for adjusting the connection between the said mechanism and the fanboard.

50. In a copying lathe, a swing frame, a model wheel carriage, a slide mounted therein, a lever pivoted on the slide and carrying a model wheel on one of its ends, a cam pivoted on the model wheel carriage and controlling the other end of the lever, a connection between the swing frame and the cam to rock the cam, a fanboard linked to the swing frame, mechanism connecting the lever and the fanboard to move the second-named end of the lever on the cam, and means for adjusting the connection between the mechanism and the fanboard comprising a periodic cam having a cycle of operation of the same time length as the rotation period of a model in the swing frame.

51. In a copying lathe, a swing frame, a model wheel carriage, a slide mounted therein, a lever pivoted on the slide and carrying a model wheel on one of its ends, a cam pivoted on the model wheel carriage and

controlling the other end of the lever, a connection between the swing frame and the cam to rock the cam, a fanboard linked to the swing frame, mechanism connecting the lever and the fanboard to move the second-named end of the lever on the cam, means for adjusting the connection between the mechanism and the fanboard comprising a periodic cam having a cycle of operation of the same time length as the rotation period of a model in the swing frame, and manually operated means for varying the cycle of operation of the cam.

52. In a copying lathe, means for holding and rotating a model and a block, a model and a cutter with their axes similarly oblique to the axes of rotation of the model and block respectively, and arranged to contact with the model and the block respectively, and means for revolving the model wheel axis around the axis of rotation of the model.

53. In a copying lathe, an oscillating frame arranged for carrying a model and a block and for rotation of the model and block therein, a model wheel and a tool arranged to co-operate with the model and block respectively, and mounted on axes similarly oblique to the axes of rotation of the model wheel and tool respectively, and means for revolving one of the said similarly oblique axes about the said axis of rotation related to it, from its normal position, through a predetermined angle, and for maintaining the angle between the normal and revolved positions, as measured from the said axis of rotation, irrespective of the position of the oscillating frame.

54. In a copying lathe, an oscillating frame arranged for carrying a model and a block and for rotation of the model and block therein, a model wheel and a tool arranged to co-operate with the model and block respectively, and mounted on axes similarly oblique to the axes of rotation of the model wheel and tool respectively, and means for revolving the model wheel axis through a predetermined angle from its normal position, about the axis of rotation of the model, and for maintaining the said angular relation between the normal and revolved positions as seen from the axis of rotation of the model irrespective of the position of the model on its axis.

55. In a copying lathe, an oscillating frame arranged for carrying a model and a block and for rotation of the model and block therein, a model wheel and a tool arranged to co-operate with the model and block respectively, and mounted on axes similarly oblique to the axes of rotation of the model wheel and tool respectively, and means for revolving the model wheel axis through a predetermined angle from its normal position about the axis of rotation of

the model, and for maintaining the said angular relation between the normal and revolved positions as seen from the axis of rotation of the model irrespective of the 5 position of the model on its axis, said means comprising a mechanism carrying the model wheel and arranged to move it in a plane at right angles to the axis of rotation of the model, said mechanism being controlled by 10 the movement of the oscillating frame.

56. In a copying lathe, an oscillating frame arranged for carrying a model and a block and for rotation of the model and block therein, a model wheel and a tool arranged to co-operate with the model and block respectively, and mounted on axes similarly oblique to the axes of rotation of the model wheel and tool respectively, and means for revolving the model wheel axis 20 through a predetermined angle from its normal position, about the axis of rotation of the model, and for maintaining the said angular relation between the normal and revolved positions as seen from the axis of rotation of the model irrespective of the 25 position of the model on its axis, said means comprising a sliding lever carrying the model wheel axis on one of its ends, a connection between the oscillating frame and the lever for swinging the model wheel center through the said predetermined angle, and a connection between the oscillating frame

and the model wheel axis arranged to rotate the model wheel axis about the model wheel center, through the same angle. 35

57. In a copying lathe, an oscillating frame arranged for carrying a model and a block and for rotation of the model and block therein, a model wheel and a tool arranged to co-operate with the model and block respectively, and mounted on axes similarly oblique to the axes of rotation of the model wheel and tool respectively, and means for revolving the model wheel axis through a predetermined angle from its normal position, about the axis of rotation of the model, and for maintaining the said angular relation between the normal and revolved positions as seen from the axis of rotation of the model irrespective of the 45 position of the model on its axis, said means comprising a sliding lever, a shaft mounted in the lever and carrying the model wheel, a controlling mechanism for the lever operated by movement of the oscillating frame, 50 arranged to swing the model wheel center through the said predetermined angle, and a controlling mechanism for the shaft arranged to rotate the shaft through the predetermined angle. 55

60 In testimony whereof I have signed my name to this specification.

LAURENCE E. TOPHAM.
